UNITED STATES PATENT OFFICE.

DARWIN COMINGS, OF SCRANTON, PENNSYLVANIA.

SANITARY BREATH DEFLECTOR.

Application filed September 21, 1921. Serial No. 502,151.

To all whom it may concern:

Be it known that I, DARWIN COMINGS, a citizen of the United States, residing at Scranton, in the county of Lackawanna and State of Pennsylvania, have invented certain new and useful Improvements in Sanitary Breath Deflectors; and I do hereby declare the following to be a full, clear, and exact description of the invention, such as will enable others skilled in the art to which it appertains to make and use the same.

This invention relates to new and useful improvements in sanitary breath deflectors, and has for its primary object the provision of means for preventing the occupants of a bed from directly breathing or inhaling the breath of the other and which is so constructed that it may be easily removed or placed in a position out of the way in the day or when not in use.

Another object of this invention is the provision of a breath deflector of the above stated character which will be simple, durable and efficient, and which may be manufactured and sold at a comparatively low cost.

With these and other objects in view as will become more apparent as the description proceeds, the invention consists in certain novel features of construction, combination, and arrangement of parts may be made without departing from the spirit and scope of the invention as claimed.

For a complete understanding of my invention, reference is to be had to the following description, and accompanying drawings, in which:—

Figure 1 is a fragmentary perspective view, illustrating my invention applied to a bed.

Figure 2 is a detail view, illustrating the support and means of connecting it to the bed.

Figure 3 is a similar view illustrating a modified form of support,

Figure 4 is a perspective view illustrating another modified form of support,

Referring in detail to the drawings, the numeral 1 indicates a supporting arm which is bent to form a loop 2 and a vertical attaching portion 3. The attaching portion 3 has its lower end bent to form a semi-circular rest or thrust bearing 4 adapted to rest on one of the transverse rounds or rods 5 of the head 6 of the bed 7. The head 6 is

of the usual construction having the vertical rods 8 and the attaching rod 3 extends parallel with one of the rods 8 and preferably the center rod 8 of the head 6 and 60 the loop 2 encircles the respective rod 8 so that the supporting rod 1 may be positioned to extend parallel with the head 6 or at right angles to said head and when in the latter named position, it supports a deflector element 9 between the faces of the occupants of the bed to prevent them from directly inhaling each other's breath.

The deflector element 9 is constructed from a suitable fabric and has secured to its 70 upper edge a suitable number of rings 10 that are mounted on the supporting arm or rod 1 so that the deflector element may be adjusted along the rod as desired. The deflector element when in an operative position has its lower edge disposed between the adjacent ends of the pillows of the bed.

From the foregoing description taken in connection with the accompanying drawings, it will be noted that a device has been 80 provided which is capable of adjustment so as to position the deflector either in an operative or inoperative position as desired and also the support may be removed and replaced on the bed when desired.

Referring to my modified form of invention as shown in Figure 3, a supporting rod or arm 11 is provided to which the deflector element 9 is attached and said rod or arm 11 has one end forked to provide diverging arms 12 which have their ends bent to form bearing elements 13 adapted to encircle one of the rods 8 of the head 6 of the bed 7 and one of said bearings 16 is provided with a set screw 14 adapted to be 95 turned against the respective rod 8 for holding the supporting arm or rod in adjusted position on the respective rod 8 and also for holding the deflector either in an operative or inoperative position.

Referring to my modified form of invention as shown in Figure 4, a vertical supporting rod 15 is provided and is formed on a base 16 and centrally of the latter. The base 16 may be of any desired shape and is 105 placed on the bed with the adjacent ends of the pillows resting on said base. The upper end of the rod 15 is formed onto a supporting rod or arm 17 on which the deflector 9 is mounted or draped.

While I have shown and described the preferred embodiment of my invention, it

will be understood that minor changes in construction, combination, and arrangement of parts may be made without departing from the spirit and scope of the invention as claimed.

Having thus described my invention what I claim is:—

1. A breath deflector comprising a supporting rod having one end bent to form a loop and a vertical portion, said vertical portion having its lower end bent to form a bearing adapted to engage a part of a bed, said loop adapted to encircle one of the vertical rods of the head of the bed, and a de-

flecting element carried by the supporting 15 rod.

2. A breath deflector comprising a support including vertical and horizontal portions, and said vertical portion having loop-shaped ends adapted to encircle a rod of a 20 bed, and a deflecting element carried by the horizontal portion.

In testimony whereof I affix my signature in presence of two witnesses.

DARWIN COMINGS.

Witnesses:

L. R. CAPWELL,
MAME E. CAPWELL.
